RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

METHOD OF HANDLING WEFT ENDS OF WEFT CARRIERS

Application filed August 14, 1930. Serial No. 475,283.

This invention relates to improvements in methods for manipulating the ends of weft threads from bobbins such as may be employed on double shuttle weft replenishing looms, and it is the general object of the invention to provide a method which will facilitate the insertion of a loop of tied ends into one or both of a pair of bobbins.

It is a further object of my invention to prove the method of handling weft ends in a replenishing magazine by not only tying the ends together but by inserting a portion of the tied ends into a part of the weft carrier.

With these and other objects in view which will appear as the description proceeds my invention resides in the combination and arrangement of parts hereinafter described and set forth in the claims.

In the accompanying drawings, wherein a convenient embodiment of my invention is set forth,

Fig. 1 is a vertical section through a portion of the magazine having bobbins arranged with their ends disposed according to the present invention,

Fig. 2 is a vertical section through a pair of bobbins showing the manner of disposing the tied ends within one of the bobbins,

Fig. 3 is a view similar to Fig. 2 but with the loops of the weft ends extending into both bobbins,

Fig. 4 is a diagrammatic view setting forth the method of drawing the tied ends into a bobbin,

Fig. 5 shows an intermediate step between the beginning and finishing of the process, with the weft end being drawn into one of the bobbins,

Fig. 6 is a side elevation of a clip used in carrying out my invention,

Fig. 7 is a front elevation taken in the direction of arrow 7, Fig. 6, and

Fig. 8 is a view similar to Fig. 4 but illustrating the manner in which the loop may be drawn into both bobbins.

It sometimes occurs in the practice of the invention set forth in Patent 1,756,709 that the weft ends will become tight so that insufficient weft remains to allow a bobbin to move from the magazine to the empty shuttle

without breaking the tied ends, this being due to rotation of the bobbins on their axes as they await transfer. Also, the tied ends of a pair of bobbins above the transfer mechanism occasionally falls from between the bobbins to a point in the path of a lower bobbin being transferred, resulting in breakage. My present invention is to be practiced in connection with the loom described in the aforesaid patent to which reference may be had for a more complete description in the manner in which the weft bobbins with their ends tied together act under varying conditions to effect continuous weaving in a weft replenishing loom.

Referring to Fig. 1, upper and lower shuttles S and S' lie horizontally opposite transferrers 11 and 12, respectively, which form part of a magazine M. A guideway 10 in the magazine receives the bobbins which are arranged in pairs, the weft ends of each pair being tied together. My present invention contemplates inserting the weft ends within one or both of the bores 13 of a pair, the upper and lower bobbins being shown at B and B', respectively.

In carrying my method into effect I may employ a structure such as that set forth diagrammatically in Fig. 4. A table 20 has projecting vertically upwardly therefrom a small post 21 to the upper end of which is secured a pair of spring clips 22 having opposed normally contacting points 23 above which are flaring sides 24 defining a notch 25 into which a weft end may fall. The post 21 and the structure carried at the upper end thereof are sufficiently small to enter the bore of the bobbin and are long enough so that when a bobbin is placed with its butt on the table 20 the opposed points 23 will be above the end of the bobbin. A knotter designated generally at 26 may be supported suitably and have operating connections 27 with a foot operated lever 28.

When practicing the present method the operator will grasp a pair of bobbins from which extend weft ends W and W', respectively and lead said ends to the knotter 26, holding the bobbins in one hand and the weft ends in the other. When leading the weft

ends to the knotter the operator will cause the threads to enter the notch 25 and pass below the spring points 23. When the thread is in this position the two ends may be held 5 in operative relation with respect to the knotter 26 which can be operated by depressing lever 28, thus uniting the weft ends W and W' by a neat weaver's knot. The bobbins are then raised together, the loop extending from 10 the bobbins to the knotter reeving under the points 23 and being drawn into the bore of one of the bobbins. When the end of the loop is reached the points 23 will spring apart due to their resilience and the loop will pass out 15 of the notch 25, remaining in the bobbin as shown in Fig. 2.

The distance between the bobbins and the knotter will ordinarily be slightly less than the length of the bobbin, or will be so proportioned that the loop which remains after 20 the threads are tied together will extend for substantially the length of the bobbin without projecting beyond the butt where it might become worn by vibration of the bobbin 25 against structure defining the guideway 10. By making the knotter adjustable as to position the method can be practiced with respect to bobbins of practically any length.

Fig. 5 illustrates an intermediate position 30 of the bobbins as they are being moved upwardly during the practice of my method, the knot K approaching the bobbins as the loop is drawn into one of them.

When it is desired to arrange the ends of 35 the bobbins as shown in Fig. 3, my above described method will be carried out in connection with two posts similar to 21 and designated herein as 40. Each post will be equipped with a device similar to that mounted 40 on the top post 21, and the knotter will be placed at substantially twice its distance from the bobbins because of the fact that there are to be two loops, one drawn into each bobbin, and there will therefore be need for 45 practically twice as much weft to form the two loops.

While I have shown a particular form of clip in Figs. 6 and 7 yet my invention can be practiced successfully with any form of 50 yielding holder which will serve to draw the loop of weft into a bobbin and release it when the end reaches the yielding part of the holder. For this reason I do not wish to be limited to the structure shown herein.

55 At the time of bobbin transfer in the loom, one of the pairs will be moved by its corresponding transferer into the associated shuttle and the weft end will be drawn out of the bore in the bobbin. My method 60 contemplates the insertion of the weft ends into the bobbin preparatory to transfer as well as the particular method by which it is accomplished herein with respect to the knotter. The neat knot may be drawn into the fabric 65 without causing a serious defect such as

would result if the ends beyond the knot were left uncut.

From the foregoing it will be seen that I have provided a simple method for inserting a loop of weft formed by tying two weft ends together into one or both of a pair of bobbins. It will also be seen that I have provided a method for improving weaving which consists in inserting the tied ends into one or both of the bobbins. 70 75

Having thus described my invention it will be seen that changes and modifications may be made therein by those skilled in the art without departing from the spirit and scope of the invention and I do not wish to be limited to the details herein disclosed, but what I claim is:

1. The method of controlling weft ends in a weft replenishing mechanism which consists in providing two bobbins having a continuous weft wound thereon, inserting a reserve of weft in one of said bobbins, and transferring one of said bobbins and leaving the other to act as a thread holder for the transferred bobbin. 80 85 90

2. The method of controlling weft ends in a weft replenishing mechanism which consists in tying the ends of weft extending from two reserve bobbins, inserting a portion of the tied ends into one of the bobbins, and transferring one of the bobbins and leaving the other un-transferred, the un-transferred bobbin acting as a thread holder to resist the pull of the weft of the transferred bobbin on the pick following transfer. 95 100

3. The method of controlling weft ends in a weft replenishing mechanism which consists in tying the ends of two bobbins together, inserting a portion of the tied ends into one of the pair so that movement of either bobbin away from the other will withdraw the end from the bobbin, and transferring one bobbin and leaving the other to act as a thread holder therefor. 105

4. The method of controlling weft ends in a weft replenishing mechanism which consists in tying the weft ends of a pair of bobbins together forming a loop, drawing the loop into one of the bobbins, and transferring one bobbin and leaving the other to act as a thread holder therefor. 110

5. The method of controlling weft ends in a weft replenishing loom which consists in tying the weft ends of a pair of bobbins together, forming a pair of loops in the weft ends, inserting one loop in one of the bobbins and the other loop in the other bobbin, and transferring one bobbin and leaving the other to act as a thread holder therefor. 115 120

6. The method of drawing weft ends into one of a pair of bobbins which consists in drawing off a predetermined amount of weft from each bobbin, tying said weft ends together to form a loop, and drawing said loop into one of the bobbins. 125 130

7. The method of drawing tied weft ends into a bobbin which consists in drawing off a predetermined amount of weft from each bobbin, tying said weft ends together at a distance from the bobbin not greater than the length of the bobbin to form a loop, and drawing the loop into one of the bobbins.

8. The method of drawing tied weft ends into bobbins of equal length which consists in drawing a predetermined amount of weft from each bobbin, tying said weft ends together at a distance from the bobbins not to exceed double the length of one of the bobbins, and drawing substantially equal portions of said tied ends into each bobbin.

In testimony whereof I have hereunto affixed my signature.

RICHARD GREENLEAF TURNER.
